SIGNAL TRANSLATING APPARATUS

Leslie J. Anderson and Alfred H. Kettler, Haddonfield, N. J., assignors to Radio Corporation of America, a corporation of Delaware

Application December 7, 1940, Serial No. 368,968

5 Claims. (Cl. 179—116)

This invention relates to signal translating apparatus, and more particularly to a sound-powered throat microphone to be worn on the user's throat and actuated by the larynx, the principal object of our invention being to provide an improved microphone of this type which is very rugged in construction and which has high sensitivity.

More particularly, it is an object of our present invention to provide an improved throat microphone which has sufficient sensitivity and intelligibility to operate directly into sound-powered telephone receivers without the need of an amplifier.

It is also an object of our invention to provide an improved microphone as set forth above which is simple in construction, is comprised of a minimum number of parts, may be readily assembled and taken apart, and which is highly efficient in use.

In accordance with this invention, we provide a microphone consisting of a casing in which are housed two diaphragms slightly spaced from each other to provide a volume of air therebetween, this volume of air constituting a fluid coupling between the two diaphragms. To one of the diaphragms is secured an actuating button which extends through a suitable opening in the casing and which rests against the wearer's throat when the microphone is applied. The other diaphragm is coupled to the vibrating reed or armature of an electromechanical signal translating unit, preferably of the balanced armature type, by means of a driving rod or the like. The air volume between the two diaphragms provides A.-C. coupling therebetween without transmitting D.-C. forces, such as are applied when the aforementioned button is pressed against the wearer's throat, thus allowing the armature to remain properly balanced in the air gap of the translating device independently of the pressure against the wearer's throat. One of the two diaphragms, preferably the second-named one, is provided with a small opening therein which affords communication between the air in the space between the two diaphragms and the air external to said space. This diaphragm opening and the volume of air between the two diaphragms are of such size that the mass of air in the opening resonates with the aforementioned volume of air preferably at the lowest frequency it is desired not to be greatly attenuated. The diaphragm opening will cause the D.-C. components due to pressure of the throat against the actuating button to be infinitely attenuated. It thus forms a simple and very effective acoustic filter in the system. The space between the two diaphragms is made such that the impedance of the air volume therein is large compared to that of the moving system constituted by the second dia-

phragm, the armature, and the connecting rod therebetween in the upper part of the spectrum it is desired to pick up (for example, in the neighborhood of 2000 to 2500 cycles). Preferably, the vibrating system which includes the second diaphragm is stiffness-controlled up to the same region, where resonance occurs. Thus, a rising frequency characteristic is obtained, which, in conjunction with the low frequency attenuation, gives intelligible speech when used without additional compensation. When used with sound-powered telephones of limited range in the lower region, the intelligibility of the system as a whole is greatly improved.

15 The novel features that we consider characteristic of our invention are set forth with particularity in the appended claims. The invention itself, however, both as to its organization and method of operation, will best be understood from the following description of several embodiments thereof, when read in connection with the accompanying drawing in which

Figure 1 is a central sectional view of one form of microphone according to our invention,

25 Figure 2 is a sectional view taken approximately on the plane of line II—II of Figure 1,

Figure 3 is a perspective view of the pole structure of the translating unit,

30 Figure 4 is a fragmentary sectional view of a slightly modified form of actuating button for the microphone,

Figure 5 is a set of response curves showing the response of our improved microphone,

35 Figure 6 is a wiring diagram showing the electrical analogy to the acoustical system of our improved microphone, and

Figure 6 is a view showing a neckband embodying, as a pair of operating units, two microphones formed according to our invention.

40 Referring more particularly to the drawing, wherein similar reference characters designate corresponding parts throughout, there is shown, in Figure 1, a casing comprised of upper and lower members 1 and 3, respectively, which may be threadedly united and the former of which is provided with an opening 5. Clamped within the casing between the portions 1 and 3 thereof are a pair of diaphragms 7 and 9 which are mounted for vibration in more or less conventional manner. To the upper diaphragm 7 is cemented or otherwise suitably secured a button 10 which extends through the opening 5 and which is adapted to be placed against the throat of the wearer when the unit is in operative position. If desired, a rubber seal 8 may be placed 45 around the button 10 and against the casing part 1. The second diaphragm 9 is connected, by means of a drive rod 11, to an armature 13 clamped at one end between a pair of pole pieces 15 and 17, preferably having overlapping pole

faces, as clearly shown in Figure 3, so that the entire assembly may be very shallow. The armature 13 operates in the air gap between the pole faces of the pole pieces 15 and 17 to which flux is supplied by a magnet 19, a coil 18 surrounding the armature 13, and the armature 13 is normally balanced so that it is disposed centrally between the pole pieces 15 and 17, as clearly shown in Figure 1.

The diaphragm 9 is provided with one or more small openings 21 which will afford communication between the volume of air in the space 23 between the diaphragms 7 and 9 and the air external to the space 23. The acoustical system described above is analogous to that shown in 15 the electrical wiring diagram of Figure 6 wherein

m_1 is the mass of the button 10 and the diaphragm 7,

c_1 is the compliance of the diaphragm 7,

c_2 is the compliance of the volume of air in the space 23,

m_2 is the mass of air in the opening or openings 21, as the case may be,

r^1 is the resistance offered by the opening or openings 21 to the passage of air therethrough,

m_3 is the mass of the vibrating system constituted by the diaphragm 9, the driving rod 11, and the armature 13,

c_3 is the compliance of the last-named vibratory system, and

r_2 represents the losses in the diaphragm 9.

Two units, such as that described above, may be assembled within the pockets 25 of a neckband 27 which is placed around the wearer's throat and suitably tightened so that the buttons 10 will be firmly pressed against the larynx. Throat or larynx vibrations are picked up by the buttons 10 and are transmitted to each of the diaphragms 7. Preferably, the buttons and their associated diaphragms should be as light as it is practical to make them and reasonably rugged. The motion of the diaphragms 7 is, in each case, transmitted to the diaphragm 9 by means of the volume of air in the spaces 23. The opening 21 in each of the diaphragms 9 is preferably of such size that the air mass therein resonates with the volume of air in the space 23 at the lowest frequency it is desired not to attenuate greatly. The openings 21 will cause the D.-C. components, due to the pressure of the throat against the buttons 10, to be infinitely attenuated. Hence, it forms a simple, though necessary, acoustic filter. Preferably, the air space 23 should be such that the impedance of the air therein is large compared to the combined impedance of the diaphragm 9, the drive rod 11, and the armature 13 up to approximately 2000 to 2500 cycles. By making the vibratory system which includes the diaphragm 9 in each case stiffness-controlled up to the same region, a rising frequency characteristic is obtained which, in conjunction with the low frequency attenuation, will give intelligible speech without requiring additional compensation.

Figure 5 shows a set of curves indicating the response which may be obtained with our improved microphone. The curve A, representing the characteristic of the larynx, shows a peak in the lower region. The curve B, representing

5 the response of our improved microphone, shows a peak in the upper region. The combination of the two is shown by the dotted line C, which represents the overall response of the larynx and our improved microphone.

In Figure 4, there is shown a slightly modified arrangement wherein the button 10 is provided with an annular shoulder 28 normally spaced from but adapted to engage the casing part 1. This may be important where, in some cases, it is desired to enable the button 10 to take great shocks without, however, transmitting them to the diaphragm 7.

Although we have shown and described but one microphone in accordance with our invention, it will be apparent to those skilled in the art that many modifications thereof, as well as changes in the one described, are possible. Therefore, we do not wish to limit ourselves except insofar as is made necessary by the prior art and by the spirit of the appended claims.

We claim as our invention:

1. A throat microphone adapted to be worn on the throat of the user for actuation by the larynx, said microphone comprising a casing, a pair of diaphragms vibratively mounted within said casing in spaced relation to each other and confining a volume of air therebetween, said volume of air constituting a coupling between said diaphragms, actuating means coupled to one of said diaphragms and extending outwardly of said casing for engagement with the throat of the wearer, an electromechanical translating device in said casing including an active element, and means coupling the second of said diaphragms to said element, said second diaphragm being provided with at least one opening therein affording communication between said volume of air and the air external thereto, said opening and said volume being of such size that the mass of air in said opening resonates with said air volume at substantially the lowest signal frequency it is desired to have the microphone translate without substantial attenuation.

45 2. A throat microphone according to claim 1 characterized in that the impedance of said volume of air is large compared with the impedance of the movable system comprised of said second diaphragm, said active element, and said coupling means therebetween within predetermined limits.

50 3. A throat microphone according to claim 1 characterized in that the impedance of said volume of air up to approximately between 2000 and 2500 cycles is large compared with the impedance of the movable system comprised of said second diaphragm, said active element, and said coupling means therebetween.

55 4. A throat microphone according to claim 1 characterized in that the vibratile system comprised of said second diaphragm, said active element and said coupling means therebetween is stiffness-controlled.

60 5. A throat microphone according to claim 1 characterized in that said translating device is of the electromagnetic, balanced-armature type of which the armature constitutes said active element.
